2 SHEETS—SHEET 2.

UNITED STATES PATENT OFFICE.

JOHN S. STEVENSON, OF BALTIMORE, MARYLAND.

SPARK-INDICATOR AND PLUG-TESTER.

1,348,456.

Specification of Letters Patent.

Patented Aug. 3, 1920.

Application filed April 29, 1918. Serial No. 231,506.

To all whom it may concern:

Be it known that I, JOHN S. STEVENSON, a citizen of the United States, residing at Baltimore and State of Maryland, have invented certain new and useful Improvements in Spark-Indicators and Plug-Testers, of which the following is a specification.

This invention relates to an improved spark indicator and spark plug tester for internal combustion engines and has as its primary object to provide a device of this character including auxiliary spark gaps adapted to be respectively included in circuit with the spark plugs and wherein the 15 said auxiliary spark gaps will be easily visible so that the occurrence of a spark at any one of the said gaps may be readily observed and the proper flow of current to the plugs thus always determined.

20 The invention has as a further object to provide a construction wherein corresponding terminals of the auxiliary spark gaps will be readily adjustable with respect to the coating terminals of the said gaps for either 25 closing the circuits at the gaps or varying the length of the said gaps to accordingly test the efficiency of the respective spark plugs.

A further object of the invention is to provide a construction wherein the terminals 30 which are mounted for service adjustment will be normally housed within the casing of the device but wherein the said casing will be provided with a door which may be opened to permit ready access to the said terminals.

35 And the invention has as a still further object to provide a device wherein the imposition of auxiliary spark gaps in the circuits of the spark plugs will prevent leakage of the current through the plugs such as might 40 be caused by defective insulation and will consequently also guard against possible resultant injury to the coils of the ignition system.

Other and incidental objects will appear 45 as the description proceeds. In the drawings wherein I have illustrated the preferred embodiment of the invention, and wherein similar reference characters designate corresponding parts throughout the several 50 views:

Figure 1 is a front elevation of my improved device showing the arrangement of the windows for the spark chambers thereof,

55 Fig. 2 is a vertical sectional view taken on the line 2—2 of Fig. 1, and particularly showing the manner in which the device is mounted in position,

Fig. 3 is a vertical sectional view taken on the line 3—3 of Fig. 1, and particularly showing the mounting of the terminals or 60 electrodes of the auxiliary spark gaps of the device,

Fig. 4 is a horizontal sectional view taken on the line 4—4, of Fig. 3,

Fig. 5 is a similar view taken on the line 65 5—5 of Fig. 3,

Fig. 6 is a rear perspective view showing the upper section of the casing of the device detached,

Fig. 7 is a view similar to Fig. 6 and illustrating the bottom section of the casing of the device detached, and

Fig. 8 is a fragmentary sectional view showing a slightly modified structure.

In carrying out the invention I employ 75 an oblong casing including a body section 10, a bottom section 11, and a top section 12. The body section is formed of suitable insulating material while the top and bottom sections may be constructed of wood. As 80 particularly shown in Fig. 7 of the drawings, the bottom section is made up of complementary mating members 13, secured together by a plurality of transversely extending screws or other suitable fastening devices 14 85 and connected at its ends with the body section by vertically disposed screws or other approved fastening devices 15 fitted loosely through the bottom section and threaded into the body section. Formed through the 90 bottom section, at suitable longitudinally spaced points thereon, is a plurality of openings 16. The top section 12 is also, as particularly shown in Fig. 6 of the drawings, made up of complementary mating members 95 17 and 18 respectively. The member 17 is connected at its ends with the body section 10 by screws or other suitable fastening devices 19 fitted through the said member and threaded into the body section while the 100 member 18 is connected with the member 17 by suitable hinges 20 and forms a door adapted to open upwardly and outwardly with respect to the body section. Connected with this door is a catch 21 of approved 105 character for normally holding the door closed. Formed through the member 18 of the top section at its lower rear edge and through the adjacent upper edge of the body section 10 is a plurality of openings 22 110 spaced longitudinally of these sections to conform to the spacing of the openings 16 in the bottom section. Connected with the body section 10 adjacent the extremities

thereof are vertically disposed attaching brackets 23 screwed or otherwise secured to the said section and provided at their extremities with laterally directed attaching lugs 24 adapted to receive bolts or other fastening means for connecting the casing to the instrument board of a motor vehicle, as conventionally indicated at 25. However, while I have indicated that the device may thus be connected with the vehicle instrument board, it will, of course, be understood that the said device may be mounted upon any other convenient part of the vehicle or, when used in connection with an engine other than a motor vehicle engine, may be mounted in any suitable place desired convenient to the engine, it being understood that the present invention is adapted not only for use in connection with the engines of motor vehicles but also in connection with internal combustion engines employed for other purposes. Nevertheless, for convenience I shall in describing the invention, refer to its use in connection with a motor vehicle engine.

Formed in the body section 10 of the casing is a plurality of cylindrical sparking chambers 26 which open through the front face of the said section to provide window openings and are diametrically enlarged adjacent their outer extremities. Seated against the shoulders thus formed in the chambers are transparent closures or windows 27. These closures may be formed of mica or other approved material and are removably held in place by spring retaining rings 28. As particularly brought out in Figs. 1, 3 and 5 of the drawings, the closures 27 are each provided with a darkened annular margin for excluding the greater portion of the light from the sparking chambers while the centers of the said closures are undarkened so that a spark occurring within any one of the said chambers may be readily observed through its window. Threaded through the body section 10 from the bottom face thereof to project at their inner ends into the sparking chambers 26, is a plurality of terminals or electrodes 29. These terminals are received through suitable recesses 30 formed in the bottom face of the said section to register with the openings 16 of the bottom section 11 and at their outer ends are provided with squared heads 31 normally projecting within the said openings and adapted to receive a wrench for adjustably rotating the terminals. As will be seen, this result may be readily accomplished by simply removing the said bottom section. However, while the terminals 29 are thus adjustable, it is intended that such adjustment shall be practically permanent so that these terminals may thus be considered as relatively fixed terminals. Threaded into the outer ends of

the terminals axially thereof are clamping screws 32 by means of which circuit wires 33 may, as particularly shown in Fig. 3 of the drawings, be connected with the said terminals. These circuit wires are, at the adjacent ends thereof, wrapped with suitable tape or otherwise formed to wedge within the outer portions of the openings 16 so as to preserve neat joints between the said wires and the casing and are respectively connected at their opposite ends to the several spark plugs of the vehicle engine.

Formed in the top face of the body section 10 opposite the recesses 30 therein, is a plurality of recesses 34 into which the openings 22 enter and threaded through the body section axially of these recesses is a plurality of sleeves 35. Loosely fitted over the said sleeves within the recesses 34 are suitable washers 36 and threaded upon the sleeves to confront these washers are nuts 37 adjustable to clamp the inner ends of circuit wires 38 between the nuts and the said washers. These circuit wires enter through the openings 22 and at their inner ends are tightly clamped therein to preserve neat joints between the wires and the casing while the opposite ends of the said wires are respectively connected with the several coils forming a part of the ignition system of the vehicle engine. It is now to be observed that the complementary mating members of the top section 12 of the casing are cut away upon their confronting sides to provide a plurality of recesses 40 overlying the recesses 34 in the top face of the body section, and receiving the upper extremities of the sleeves 35. The sleeves are internally threaded adjacent their inner ends and adjustable through the said sleeves are screw terminals or electrodes 41 projecting at their inner extremities into the sparking chambers 26 of the body section in alignment with the relatively fixed terminals 29. At their upper extremities the terminals 41 are received within the recesses 40 of the top section and are equipped with annular heads 42 of suitable insulating material. Bearing between these heads and the nuts 37 are tensioning springs 43 yieldably holding the said terminals and nuts at adjustment.

As will now be clear, the pairs of coating terminals 29 and 41 will form auxiliary spark gaps within the sparking chambers 26 and these auxiliary spark gaps will be interposed in the circuits of the engine spark plugs. Consequently, each time a circuit is closed through the several wires 38, a jump spark will occur within one of the sparking chambers and since the wires 33 are preferably connected with the spark plugs of the engine in the order of firing of the cylinders thereof, it may thus be readily determined, by observing the jump sparks in the sparking chambers through the win-

dows thereof as to whether or not all of the spark plugs are properly operating. Furthermore, in thus interposing auxiliary spark gaps in the circuits of the spark plugs, 5 leakage of current through the plugs, such as might be caused by defective insulation, will be overcome, since current can flow to the plugs only when the voltage of the current has raised sufficiently to jump the auxiliary spark gaps.

As particularly brought out in Fig. 3 of the drawings, the terminals 41 will be inclosed and housed by the upper section 12 of the casing when the door of this section 15 is closed. However, by opening this door access may be readily had to the said terminals. Consequently, by grasping the heads 32 of the terminals, these terminals may be easily adjusted with respect to the terminals 20 29 for varying the length of the auxiliary spark gaps and, since the heads of the terminals are formed of insulating material, this operation may be performed while the engine is running. The terminals 41 may thus 25 be regulated for varying the length of the auxiliary spark gaps under working conditions of the engine to accordingly obtain the most effective operation of the ignition system thereof while, in a similar manner, the 30 said terminals may also be adjusted to engage the terminals 29 to thus close the circuits therethrough for testing the spark plugs in a manner which will be well understood. Upon the setting of the terminals, 35 the springs 43 will prevent their accidental displacement from adjusted position.

It will, therefore, be seen that I provide a particularly efficient construction for the purpose set forth and while in the present 40 instance I have shown and described the embodiment of my invention as applying to a four-cylinder engine still, it will, of course, be understood that the device may be readily modified for use in connection with engines 45 having either a greater or less number of cylinders.

In Fig. 8 of the drawings I have shown a slight modification of the invention which relates more particularly to the provision of 50 centrally apertured light screens in connection with the closures for the sparking chambers. In this figure, one of the sparking chambers is indicated at 43. The window of this chamber is closed by a transparent closure 44. Seating against the outer face of this closure is a light screen 45 which may be constructed of a darkened piece of mica or other approved material for shading the outer margin of the closure to exclude the 55 passage of light therethrough. The screen 45 is held in position by a spring retaining ring 46 similar to the rings 28 of the preferred construction. In some instances it may be found preferable to employ this light 60 screen of the modified structure in lieu of the 65

colored or darkened closure proper as illustrated in connection with the preferred form of the invention.

Having thus described the invention, what is claimed as new is:

1. A device of the character described including a casing provided with a sparking chamber, a sleeve opening into the chamber, coacting terminals projecting into the chamber and forming a spark gap therein, one 75 of said terminals being fitted through the sleeve and rotatably adjustable thereon with respect to the other of the terminals, means adjustable upon the sleeve for clamping a circuit wire in engagement therewith, and 80 yieldable means bearing between said first mentioned means and the adjustable terminal for holding such terminal at adjustment and also holding said first mentioned means at adjustment.

2. A device of the character described comprising a body section and top and bottom sections mating with the body section, fastening means connecting said sections, the body section being formed with a sparking 90 chamber and the bottom section with an opening, a terminal fitted through the body section into the chamber and accessible through said opening, and a terminal normally housed within the top section and 95 projecting through the body section into said chamber to coact with said first mentioned terminal.

3. A device of the character described including a casing comprising a body section, and a top section including a fixed member connected to the body section, and a movable member hingedly connected to the fixed member and providing a door for the said top section, the body section being 100 provided with a sparking chamber, a relatively fixed terminal carried by the body section to project into the said chamber, and a terminal adjustable upon the body section and projecting into the said sparking chamber to coact with the said first mentioned terminal, the said adjustable terminal 105 upstanding within the top section of the casing and being accessible for adjustment upon the opening of the said door.

4. A device of the character described including a casing split horizontally to provide a body section and a top section, the top section being split vertically to form a fixed member connected to the body section, 115 and a movable member hingedly connected to the fixed member and providing a door, and coacting terminals carried by the body section, one of said terminals projecting within the top section and being accessible 120 upon the opening of said door.

In testimony whereof I affix my signature.
JOHN S. STEVENSON. [L. s.]
